ILLUMINABLE COSMETIC MIRROR

Robert Prouty, 4229 Elliot, Dayton, Ohio 45410, and
William M. Carmody, 214 Magnolia Lane, Fairborn,
Ohio 45324

Filed Sept. 22, 1965, Ser. No. 87,112

Term of patent 14 years

(Cl. D86—10)

FIG. 1 is a perspective view of an illuminable cosmetic mirror embodying our design, as observed from the top thereof;

FIG. 2 is a perspective view of the illuminable cosmetic mirror observed from the bottom thereof;

FIG. 3 is an end view of the illuminable cosmetic mirror as shown in FIGS. 1 and 2;

The design is characterized by a base plate providing a plate surface bounded on one end by a generally rectangular housing having a flat planar front panel in which is installed a distinguishing plate section and through which projects a relatively small lamp for pinpoint illumination; a mirror being provided on said base plate surface and being partially hooded by tapering sides rising from said base plate surface to said rectangular housing.

We claim:

The ornamental design for an illuminable cosmetic mirror, substantially as shown and described.
